WALKING BEAM TRANSFER DEVICE

Emil Umbrecht, Northville, and William J. Burman, Detroit, Mich., assignors to Ajem Laboratories, Inc., Livonia, Mich.

Filed Aug. 21, 1962, Ser. No. 218,358
12 Claims. (Cl. 198—20)

The invention relates to transfer devices and more particularly to devices adapted to transfer a plurality of articles from station to station in succession along a path. 10

Heretofore, there has been need for a transfer device capable of accelerating from a start position first upward to pick up articles, and especially heavy articles, e.g., engine blocks, and then forward, and decelerating again to stop the forward motion, and finally setting the article down at a second location, in a very precise manner, e.g., on locating pins engaging small holes in the article, which must not suffer damage from inertial impacts. To this end it is important to have the vertical movement of lifting and setting down substantially free from horizontal components so that a given point on the article to be transferred will follow a rectilinear path accurately aligned with the locating device.

It is, therefore, an object of the invention to provide a transfer device having separate periods of vertical and horizontal movement.

Another object of the invention is to provide a transfer device capable of smooth acceleration and deceleration, both vertical and horizontal, so as not to cause shock to the article or equipment.

Another object of the invention is to provide a transfer device capable of accelerating from a start position to pick an article off from small and fragile locating means and, subsequently to decelerate while lowering the article in a precise manner at a second location onto small and fragile locating means.

Another object of the invention is to provide a transfer device capable of positively holding articles throughout the sequence of its operation.

Another object of the invention is to provide a transfer device adaptable to operation to different elevations, and adaptable to a wide range of speeds.

A still further object of the invention is to provide a transfer device which is dependable, rugged, compact, uncomplicated, and relatively inexpensive involving no undue maintenance and service.

Other objects and a fuller understanding of the invention will appear from the following description and claims, taken in conjunction with the accompanying drawings in which:

FIGURE 1 is a fragmentary view in side elevation taken on line 1—1 of FIGURE 3, showing a device embodying the present invention;

FIGURE 2 is a view partly in elevation, partly broken away and partly in section, taken on line 2—2 near the left end of FIGURE 3;

FIGURE 3 is a top plan view of the device but with only the location of certain parts shown by dot-dash lines; and

FIGURE 4 is a side elevation of the same end of the device as shown in FIGURE 1, but taken from the right side of FIGURE 2.

Referring to these drawings, a frame 10 is shown of heavy metal construction and having sides 10a and 10b, and extension 10c, and a pair of opposite, substantially parallel, longitudinally extending, substantially horizontal, stationary rest supports 11a and 11b located at the top of frame 10. Rest supports 11a and 11b may have rest saddles or holding pins thereon for locating the articles accurately in place.

A first shaft 12 is rotatably mounted at the left end

2

of FIGURES 1, 3 and 4 substantially perpendicular to the stationary rest supports 11a and 11b in bearings 12a and 12b shown in FIGURE 3. A first sprocket wheel 13 of relatively large diameter is keyed on the right end 5 of shaft 12. A gear reducer 14 (see FIGURES 3 and 4) having an output shaft 15, with sprocket 17 keyed thereon and an input shaft 16, is positioned to align the sprocket wheels 13 and 17, which are connected in tandem with sprocket chain 18.

An electric motor 19 is positioned beyond the gear reducer 14 and having a drive pulley aligned with a pulley on the input shaft 16 and connected by a V-belt 20. Overload protecting means 21 may be provided for the electric motor 19, e.g., a slippable friction-type clutch, a shear pin, or other safety coupling, or a magnetic brake.

Turning now to the left end of FIGURE 1, a cam wheel 22 is fixedly connected to first shaft 12 to turn therewith. Cam wheel 22 provides a lift period 23, a high-dwell period 24, a lowering period 25, and a low-dwell period 26, assuming that it is rotating in a counter-clockwise direction. It is within the scope of the invention to have cam wheel 22 rotate either way.

Near the top of FIGURE 2, a second shaft 27 substantially parallel to the first shaft 12 is shown rotatably mounted in bearings 27a and 27b between the sides 10a and 10b of frame 10. A first lift arm 28a and a second lift arm 28b are fixed (e.g., keyed, pinned or splined, etc.) on the shaft 27 in spaced relation and substantially parallel to each other. Flanged rollers 29a and 29b are connected to the free ends of lift arms 28a and 28b respectively and extend laterally therefrom.

A cam follower wheel 30 is pivotally mounted at an intermediate position on the lift arm 28b and extends laterally therefrom, to coast with cam wheel 22.

It is within the scope of the invention to have a second cam wheel 22 and a second cam follower 30 located to cooperate with lift arm 28a, in which case the arms 28a, 28b would not need to be keyed together. The distance from the first cam follower 30 to the second shaft 27 determines the amplitude of upward swing of the cam followers at lift arms 28a and 28b, and therefore the lift of the rollers 29a and 29b.

The closer cam follower 30 is to the second shaft 27, the greater the upward swing, and, for a given arm length the greater the lift. The difference between radii of the rest period 26 and the high-dwell period 24 of cam wheel 22, other things being constant, also determines the upward swing, and the lift, of the lift arms 28.

A third shaft 31 is rotatably mounted in bearings 31a and 31b (see the right end of FIGURE 3), respectively on frame 10 and is substantially parallel to the shafts 12 and 27. Third and fourth lift arms 28c and 28d are fixedly connected to the third shaft 31 in spaced relation substantially parallel to each other and substantially parallel, and in tandem with, the first and second lift arms 28a and 28b respectively. Flanged rollers 29c and 29d are connected to the free ends of lift arms 28c and 28d respectively extending laterally therefrom in tandem with the flanged rollers 29a and 29b, respectively, of first 55 and second lift arms 28a and 28b. It is within the scope 60 of the invention to have additional lift arms.

Referring back to FIGURE 2, a pair of opposed substantially parallel transfer bars 32a and 32b define the carrier or transverse member of this embodiment, and each rides on the rollers 29a-d of lift arms 28a-d, respectively. These bars are adjacent to, and parallel to, the stationary rest supports 11a and 11b. Rollers 29a-d have flanges 33a-d respectively which hold bars 32a and 32b thereon and prevent lateral displacement. A series of cross bars 35 (FIGURE 2) rigidly interconnect transfer bars 32a and 32b, and carry vertical cam bars 53. Transfer bars 32a and 32b may have rest supports, or saddles,

or holding pins for holding articles in place, not shown.

Shafts 27 and 31 extend laterally beyond the righthand side 10b of frame 10, as shown in FIGURES 2 and 3. Shafts 27 and 31 have double yoke crank arms 36 and 37 respectively fixedly connected thereto and extending upward therefrom. A connecting rod 34 is pivotally connected between the crank arms 36 and 37 to cause shafts 27 and 31 having lift arms 28a-d to move in concert.

A stationary cam 38 is fixedly connected to frame 10, for example by welding or bolting, as shown in the left-hand portion of FIGURE 2 and as best seen at the left-hand portion of FIGURE 1. Stationary cam 38 has flattened vertical edges 39 and 40 straight or described by arcs having radii substantially larger than the radius of the circular stationary cam 38, for reasons presently to be explained. It is within the scope of the invention to vary otherwise the shape of the circumference of stationary cam 38.

Referring to FIGURES 1-3, a crank arm 41 is fixedly mounted on the end of shaft 12 just beyond the stationary cam 38 and substantially at the mid-point of the low dwell 26 of cam wheel 22. A lost motion connection 42, advantageously, as shown, an L-shaped clevis link, is pivotally attached at one end of the arms 41. The outer end 42a of the L-shaped link 42, extends laterally therefrom and is positioned to follow the periphery of, and coact with, the stationary cam 38. A stop pin 45 is located on crank arm 41 so that end 42b of L-shaped link 42 bears against it when cam follower 44 rides on the circular part of stationary cam 38.

Referring now to FIGURE 2, a fourth shaft 46 is located at the bottom of frame 10 extending between the longitudinal frame members 10c and 10d substantially parallel to first, second, and third shafts 12, 27 and 31 respectively. Shaft 46 is located at the intermediate portion of frame 10 as seen in FIGURE 1. A double lever 47 is rotatably mounted on shaft 46 and a connecting rod 48 is pivotally connected to and between L-shaped link 42 and lever 47 at pins 49 and 50 respectively. The arms of lever 47 are designated 47a and 47b and are rigidly connected by a strut 47c.

The horizontal sweep of the free end of lever 47 is determined by the location of pin 50 on lever 47. The closer the pin 50 is to shaft 46, the greater the sweep. Adjustable stop bolts 51 and 52 (FIGURE 1) are positioned to limit the to-and-fro movement of lever 47 so that cam follower 44 does not move beyond the flattened vertical edge portions 39 and 40 respectively of stationary cam 38.

A vertical cam 53 is rigidly connected to transfer bars 32a and 32b as seen in FIGURE 2, and at an intermediate location in FIGURE 1. As shown, cam 53 is indirectly mounted on bars 32a and 32b by a cross bar 35. Cam 53 includes opposed depending vertical faces defining a channel therebetween, closed by a stop located at the bottom end of cam.

The end of lever 47 has a cam follower roller 57 which engages the opposed cam faces 53. Arms 47a and 47b straddle the cam 53.

Referring now to the right hand portion of FIGURE 2, a sprocket wheel 58 is fixedly connected to first shaft 12 to rotate therewith. A timer 59 is located in close proximity to sprocket wheel 58 with its own in-put sprocket wheel 61 connected thereto by drive chain 62. It is appreciated that other means may be used to actuate timer 59. This timer may be used to energize and de-energize electrical devices at predetermined points in the transfer cycle, e.g., solenoid valves for washing jets, etc., to synchronize in the cycle.

In operation, the rotation of cam wheel 22 in FIGURE 1 and coaction of cam follower 30 cause lift arm 28b to swing upward and downward. Since lift arm 28a is fixedly connected to the second shaft 27, which also carries lift arm 28b, these move in concert; and, since shaft 27 is connected to shaft 31 through the interaction of connect-

ing rod 34 (as seen in the upper right-hand portion of FIGURE 2 and lower portion of FIGURE 3). Lift arms 28c and 28d, fixed on shaft 31, also move in concert with lift arm 28b. Lift arms 28a-d elevate and lower transfer bars 32a and 32b to lift an article off, or lower an article onto, stationary rest supports 11a and 11b.

Horizontal transference to different positions on stationary rest supports 11a and 11b is accomplished by the to-and-fro movement of lever 47, as seen in FIGURE 1. Cam driver 57 rolls along (or within the broad terminology of the claim language "slides") in the vertical channel of cam 53 and thus converts the sinusoidal motion of roller 57 to purely horizontal motion as applied to the transfer bars 32. Cam 53, however, permits vertical motion of transfer bars 32a and 32b, although it does not transmit it. It is permissible within the broad scope of the invention to modify the contour of channel 55 for special effects, e.g., according to the specific inventions of one of us and our co-workers as described in copending applications. It should be further noted that lever 47 and connecting rod 48 are in effect "a motion multiplier" for increasing the horizontal throw of crank arm 41. When the horizontal throw of crank arm 41 alone is sufficient, this invention can be effectively practiced by having roller 44 bear directly on surface 53.

Rectilinear motion of transfer bars 32a and 32b with sharp change from longitudinal to vertical and vice versa is accomplished by means of stationary cam 38. When cam follower 44 is on the flattened vertical dwell 39 or 40 of stationary cam 38, when the vertical motion of transfer bars 32a and 32b should be the greatest, for the cam follower 30 is on its lift period 23 or the lowering period 25 of cam wheel 22. The cam follower 44 proceeds along the dwell 39 while cam follower 30 is lifted by cam 22. The horizontal component of the motion of lever 47 and connecting rod, meanwhile, is negligible or completely arrested, depending on the exact shape of the flattened portion 39 on cam 38; this occurring preferably while vertical motion is being generated by the cam follower 30 riding along the lift period 23 of cam 22. Contouring stationary cam 38 with flattened vertical edges 39 and 40 thus reduces horizontal motion while vertical motion is occurring, and thus provides close to perfect rectilinear motion of the transfer bars 32a and 32b. By giving the flattened dwells a slight arc, concave at 40 and convex at 39 with radius equal to the length of 48 between pivots, all horizontal motion will cease to be generated; and if the vertical motion generated by cam 32 is properly timed, then exact rectilinear motion results.

L-shaped link 42 holds cam follower 44 against the circular portion of the circumference of stationary cam 38 by its end 42b bearing against stop pin 45. When the cam follower 44 reaches one of the flattened portions 39 or 40 of stationary cam 38, adjustable stop bolts 51 and 52 hold the cam follower 44 against the flat on cam 38, 55 while the lost-motion link 42 accommodates the arcuate motion of the crank 41. At these times, end 42b of link 42 swings away from stop pin 45. In the particular example illustrated, the angle that lever 47 can move between stop bolts 51 and 52 has been arbitrarily set at 85°30'. It is, 60 of course, within the scope of the invention to vary the angle according to the desired throw of the bars 32. Other lost-motion links can be used instead of the L-shaped pivoted link shown. Two requirements for such other lost-motion linking means, which from this disclosure would be evident to a mechanic skilled in the art, are (1) to have means for keeping roller 44 engaged on the peripheral surface of cam 38 (e.g. spring loading the roller or having it ride in a cam groove) and (2) to have means for mounting roller 44 radially movable relative 65 to the crank arm thereby enabling the roller to follow the cam 38 as it deviates from a circle (e.g. slidably mounting the roller along the crank arm).

The timer 59 may be used to energize stopping mechanisms on electrical motor 19 (see FIGURE 4) to hold the articles in their respective positions for the time required

for the operations being performed. The stopping device used for this function may also be energized by an overload relief device, e.g., centrifugal switch 65, to stop the operation until restarted by the operator after the abnormal condition, such as the overload, is corrected.

It must be appreciated that in practice the transfer may be of a single article or a series of articles which can be accommodated in a number of stations, respectively, in the length provided for by the transfer device. The transfer device provided by this invention isolates in successive periods vertical motion and horizontal motion and provides for acceleration of articles in each direction and for deceleration before setting them down again at another station.

Although the invention has been described with some particularity, it is to be understood that the particular embodiment shown and the variations described have been given by way of example, and numerous changes in the details of construction and the combination and arrangement of parts may be resorted to without departing from the spirit and scope of the invention.

We claim:

1. A transfer device adapted to transfer a plurality of articles in succession from station to station along a path, which comprises spaced stationary rest supports, a pair of liftable and longitudinally slidable transfer bars connected to said rest supports, rotary cam means coacting with said transfer bars to impart vertical motion thereto, rotating drive means for said cam means, a lever pivotally anchored relative to said rest supports and slidably engaging a bearing surface transverse to, and connected to, said transfer bars, a crank arm means operatively connecting said crank arm to said rotating drive means, a stationary cam coaxial with said crank arm and having substantially flattened opposite faces, a connecting link including a lost-motion connection between said crank arm and said lever, and a cam follower coacting with said stationary cam to activate said lost-motion connection at positions corresponding to said flattened faces and thereby avoid imparting longitudinal motion to said transfer bars at such position.

2. A transfer device adapted to elevate a first article from a first station, to move the article along a path towards a second station, to lower the article into the second station, and to successively repeat the above cycle with succeeding articles, which comprises a frame having laterally spaced substantially parallel longitudinally extending stationary rest supports at the top thereof; a shaft rotatably mounted on said frame substantially perpendicular to the longitudinal direction of the stationary rest supports; drive means for said shaft; a cam wheel connected to said shaft to turn therewith having a lift period, a high-dwell period, a lowering period, and a low-dwell period; a pair of lift arms, each having one end pivotally connected to said frame at points respectively spaced longitudinally, and having their outer ends being positioned and adapted for substantially free sliding movement on a transfer bar hereinafter specified and one of said lift arms having a cam follower positioned to coact with said cam wheel; another pair of lift arms pivotally connected to said frame in laterally spaced relationship to said first named pair and in tandem with, and substantially parallel to, each other and their outer ends being positioned and adapted for substantially free sliding movement on said transfer bars; a first transfer bar slidably supported on one pair of arms; a second transfer bar slidably supported on the other pair of arms and connected to, and substantially parallel to, said first-named transfer bar; a stationary cam fixedly connected to said frame coaxial with said shaft and having flattened sectors on opposite edges; a crank arm fixedly connected to said shaft to rotate therewith adjacent to said stationary cam and positioned to substantially bisect one of the dwells of said cam wheel; a lost-motion pivotal connection on said crank arm radi-

ally spaced from said shaft; a lever pivotally connected to said frame to swing on an arc with a horizontal component; a connecting rod pivotally connected between said lever and said lost-motion connection; a cam follower connected to said crank through said lost-motion connection and extending laterally over the edge of, and positioned to coact with, said stationary cam; a slotted member fixedly and transversely attached to one of said transfer bars; and a drive bearing connected to said lever, extending into, and substantially fitting, the lateral slot thereof and positioned to coact with said slotted member to drive the transfer bar longitudinally when the lever is swung.

3. A transfer device adapted to elevate a first article from a first station, to move the article along a path towards a second station, then to lower the article into the second station, and to successively repeat the above cycle with succeeding articles, which comprises a frame having rest supports at the top thereof; a cam and means for driving it, said cam having a lift period, a high-dwell period, a lowering period, and a low-dwell period; lift arms, each pivotally connected to the frame and an end of each being adapted to slide on a transfer bar hereinafter mentioned, and one of said lift arms having a cam follower connected thereto and positioned to coact with said cam, at least two of said lift arms being spaced longitudinally, and means pivotally connected to both, tying them together at the same radii from the axes of their respective pivot connections to the frame and at the same distance apart as that between the axes of said pivotal connections whereby said arms operate in tandem with, and always substantially parallel to, each other; a carrier transfer bar slidably supported on the lift arms, a substantially circular stationary cam fixedly connected to said frame coaxial with said driven cam and having flattened opposite edges described by arcs having radii substantially longer than the radius of said circular stationary cam; a crank arm mounted to rotate adjacent and coaxial with said stationary cam and substantially to bisect the high-dwell and low-dwell periods of said driven cam; an L-shaped link having one end pivotally connected to the outer end of said crank arm; a lever pivotally connected to the frame; a connecting rod having one end pivotally connected between said link and said lever at a substantial radius from its connection on the frame; a cam follower on said link positioned to coact with said stationary cam; a vertically slotted member fixed on and depending from one of said transfer bars; and slide means on said lever, extending into said slot to coact with said vertical guide.

4. A transfer device as defined in claim 3 in which at least one of the flattened portions of the stationary cam are arcuate with substantially greater radius than the radius of the intermediate portions of the cam.

5. A transfer device adapted to transfer a plurality of articles in succession from station to station along a path comprising a pair of opposed substantially parallel longitudinally extending substantially horizontal stationary rest supports, each having a first end, a second end, and an intermediate portion; a shaft rotatably mounted at the first ends of said rest supports substantially perpendicular thereto; rotating means for said shaft; a cam wheel on said shaft connected to turn therewith having a lift period, a high-dwell period, a lowering period, and a low-dwell period, a plurality of lift arms of substantially equal length, one end of each being pivotally connected to said rest supports and one of said lift arms having a cam follower roller extending laterally therefrom positioned to coact with said cam wheel; a pair of opposed substantially parallel transfer bars, slidably carried on the second ends of said lift arms, whereby they are kept substantially parallel to said rest supports; a stationary cam fixedly connected to said frame coaxial with said shaft and having flattened opposite vertical edges; a crank arm fixedly connected to

axial to said shaft, to rotate therewith, and adjacent said stationary cam substantially bisecting the high and low dwells of said cam wheel; stop means at an intermediate portion of said crank arm extending laterally therefrom; an L-shaped link with its intermediate portion pivotally connected to the outer end of said crank arm and the foot of its L positioned to bear against said stop means; a lever pivotally mounted and connected to the intermediate portion of said stationary rest supports; adjustable stop means to limit to desired amplitude the to-and-fro movement of said lever and thereby the longitudinal transfer of said articles; a connecting rod having the one end pivotally connected to the intermediate portion of said lever and the outer end pivotally connected to the outer end of said L-shaped link; a cam follower connected to the outer end of said L-shaped link, extending laterally therefrom over said stationary cam to coact therewith; a vertical bearing surface fixedly protective from the transfer bars; and a cam driver connected to the outer end of said lever, extending laterally therefrom, and positioned to coact with said vertical bearing face.

6. A device as described in claim 5 which further includes a timer for timing the idle periods of said electric motor to correspond with periods of desired operations at said stations.

7. A transfer device adapted to transfer at least one article from station to station along a predetermined path, which comprises a machine frame; a transfer member; rotary drive means; means for converting said rotary drive to individually controlled reciprocating vertical motion; means for converting the rotary drive to individually controlled reciprocating horizontal motion including a crank arm rotatably mounted on said machine frame and operatively connected to said rotary drive means, a stationary substantially circular cam having substantially flattened opposing peripheral dwell faces, said stationary cam being fixed to said machine frame coaxial with said crank arm, a vertical-lost-motion means for imparting only the horizontal component of motion derived from said rotary drive means through said crank arm, this vertical-lost-motion means defining a vertical channel and including an anti-friction driver riding in said channel, and connecting means extending between said crank arm and said anti-friction driver for imparting at least a substantial portion of the horizontal motion generated by said crank arm to said driver, said connecting means being pivotally attached to the free end of said crank arm and including a lost-motion linking means adapted to follow the periphery of said stationary cam thereby at least substantially interrupting the horizontal motion conveyed there-

between when said lost-motion-linking means transverses the dwell faces of said stationary cam.

8. A transfer device as defined in claim 7 wherein the dwell faces of said stationary cam are vertically flat throughout at least a substantial portion of each dwell face.

9. A device as described in claim 7 wherein the two oppositely disposed dwell faces of the stationary cam are flattened to accommodate a predetermined portion of the horizontal motion generated by said crank arm.

10. A transfer device adapted to transfer at least one article from station to station along a predetermined path, which comprises a machine frame; a transfer member; rotary drive means; means for converting said rotary drive to individually controlled reciprocating vertical motion; means for converting the rotary drive to individually controlled reciprocating horizontal motion including a crank arm rotatably mounted on said machine frame and operatively connected to said rotary drive means, a stationary substantially circular cam having substantially flattened opposing peripheral dwell faces, said cam being fixed to said machine frame coaxial with said crank arm, a vertically slotted member fixed to and depending from said transfer member, a lever pivotally anchored to said machine frame and slidably engaged at its free end in said vertically slotted member, a connecting rod extending between said crank arm and said lever and being pivotally connected at one end to an intermediate portion of said lever, and a lost-motion linking means connecting said other end of said rod with the free end of said crank arm and including a cam follower mounted on said other end of said connecting rod, which cam follower coacts with the peripheral surfaces of said stationary cam to activate this lost-motion linking means while it traverses said dwell faces thereby absorbing a predetermined portion of the horizontal motion being conveyed to said transfer member.

11. A device as described in claim 10 where said lost-motion linking means comprises an L-shaped link pivotally connected at one arm to said connecting rod, a stop mounted on said crank arm to engage the inside of the other arm of said L-shaped link to prevent said cam follower from disengaging the circular portions of the stationary cam.

12. A device as described in claim 11 further including stop means for delimiting the maximum arc of said lever.
